UNITED STATES PATENT OFFICE.

RAYMOND W. BURNS, OF POUGHKEEPSIE, NEW YORK, ASSIGNOR TO JAMES L. TAYLOR
MFG. CO., A CORPORATION OF NEW YORK.

PRESSURE-FOOT ATTACHMENT FOR CLAMPS.

Application filed March 24, 1923. Serial No. 627,270.

To all whom it may concern:

Be it known that I, RAYMOND W. BURNS, a citizen of the United States, and a resident of Poughkeepsie, in the county of Dutchess 5 and State of New York, have invented new and useful Improvements in Pressure-Foot Attachments for Clamps, of which the following is a specification.

In clamps which are used for clamping up 10 glued work such as backs of school seats and the like, whether flat or curved, a pressure foot is commonly used to conform to the contour of the work and hold it against bulging or springing upward as it is 15 clamped at its opposite edges in gluing together the pieces of which it is made, said pressure foot being commonly carried on a rod mounted on the body of the clamp, usually over the work. The present invention 20 relates to such a pressure foot, and more particularly to the means for supporting it on such a rod or carrier.

The objects of the invention are to secure 25 an improved construction of adjustable support so that the pressure foot can be adjusted toward or away from said rod or other support to accommodate different thicknesses or 30 heights of work; to secure such adjustability without the necessity of separating the different parts of the device in adjusting 35 it; to thus avoid detachable parts which may be mislaid and lost; to secure a simple and easily operated construction which shall be strong and not liable to get out of order; 40 to secure minimum displacement of the pressure foot longitudinally of its support by reason of its adjustment toward or away from the same, and to obtain other results and advantages as may be brought out by the following description.

Referring to the accompanying drawings, in which the same characters of reference designate corresponding and like parts,

Figure 1 is a side elevation of a pressure 45 foot attachment embodying my invention, showing the same in connection with a known type of clamp and in idle position;

Figure 2 is an enlarged vertical longitudinal sectional view through the pressure 50 foot attachment showing the same in operative position, and

Figure 3 is a transverse vertical sectional view taken on the line 3—3 of Figure 2.

For the purpose of illustrating the principles 55 of the invention, I have shown the pres-

sure foot P in connection with a well-known type of clamp used on clamp machines and including a body portion A having secured at one end a spanner foot or base B which is provided transversely of the body A with 60 forked ends C and E to receive two cross rods D, D, of a clamp machine. The other end of the body portion A has secured thereto a fixed jaw F to cooperate with an adjustable jaw G slidable on the body portion and moved into and out of clamping position by means of well-known mechanism including a screw and a handled nut H. In such a clamp the pressure foot is usually carried by a rod I pivotally mounted in the base B, 65 as at K, and normally swung into inoperative position away from the work by means of a spring L, said rod I being held in operative position to force the pressure foot 70 against the work by means of a hook M pivotally mounted on the fixed jaw F.

The pressure foot P is preferably channel-shaped and provided with longitudinal side flanges 1 which project at substantially right angles from the base 2 and have a pin 3 passing therethrough at substantially the central point in the length thereof. The said pin 3 is loosely mounted in a slot 4 in a depending arm 5 of a supporting member 6 which is shown in the present instance in the 80 form of a tubular slide mounted to move longitudinally of the rod I and held in adjusted position thereon by means of a set screw 7. The slot 4 is provided at its upper side with a plurality of notches or seats 8 to receive the pin 3, said seats being disposed at different distances from the rod I.

When clamping a piece of work, the rod I is swung downwardly and hooked under the hook M with the pin 3 of the pressure foot 95 attachment arranged in one of the seats 8, whereby the pressure foot P is forced against the top of the work W on the clamp body A, as shown in Figure 2, and prevents the work from bulging upwardly as it is clamped between the jaws F and G. The particular one of the recesses 8 in which the pin 3 is inserted is determined by the thickness of the work on the clamp, the pin being placed in one end recess when the work is of minimum thickness, as shown by dot and dash lines in Figure 2, and in the other end recess when the work is of maximum thickness. It is thus possible to adjust the pressure foot P toward 100 or away from the rod I in order to accommo- 105

date different thicknesses of work. When the work is to be removed from the clamp the bar I is released from the hook M, whereupon it is swung upwardly by the spring 5 L into the position shown in Figure 1, and the pressure foot P then falls by action of gravity out of its seat and into the bottom of the slot 4.

It will be observed that the adjustment 10 of the pressure foot P to accommodate various thicknesses of work is accomplished without separating it from its supporting member 6, thereby preventing the misplacing or loss of any of the parts and insuring 15 a minimum amount of time being consumed in making the adjustment. It will also be noted that the adjustment of the pressure foot is made with a minimum movement of the pressure foot longitudinally of the support 20 I. Preferably the underside of the slot 4 is substantially parallel to the series of seats 8 in the upper side of the slot and thus inclined to the horizontal, so that when the pressure foot P drops by gravity its pin 25 3 will automatically position in one end of the slot. Thus the operator in adjusting the pressure foot always moves it in the same direction, and as it is easier to push the pressure foot away from him in making 30 such adjustment the slot preferably inclines toward the front end of the clamp.

While I have shown the pressure foot attachment embodying certain details of construction, for illustrative purposes, it 35 will be understood that many modifications and changes can be made in the details of the attachment without departing from the spirit or scope of the invention. The attachment can be used on other types of 40 clamps, and I wish to be understood as not limiting myself except as required by the following claims when construed in the light of the prior art.

Having thus described the invention, what 45 I claim is:

1. The combination with a clamp having a work supporting body, and a pressure foot rod, of a pressure foot to engage work on said body, and a support on said rod for 50 permanently supporting said pressure foot and having a plurality of seats to selectively receive said pressure foot to accommodate work of different thicknesses while so permanently supported.

2. The combination with a clamp having a work supporting body, of a pressure foot to engage work on said body, a support for 55 said pressure foot having a slot therein formed with a plurality of seats, and means 60 in said slot to mount said pressure foot on said support, said means being adapted to selectively engage any of said seats to adjust said pressure foot for accommodating work of different thicknesses.

3. The combination with a clamp having 65 a work supporting body, of a pressure foot to engage work on said body, a support for said pressure foot having a plurality of seats to selectively receive said pressure foot to accommodate work of different thicknesses, and means for mounting said pressure foot on said support to automatically by action of gravity release itself from any of said seats when in idle position.

4. The combination with a clamp having 70 a work supporting body, of a pressure foot to engage work on said body, and a support for said pressure foot having a plurality of seats to selectively receive said pressure foot to accommodate work of different thicknesses, said support also having means for automatically moving said pressure foot when idle toward one end of the clamp.

5. The combination with a clamp having 75 a work supporting body, of a pressure foot to engage work on said body, a support for said pressure foot having a slot therein inclined with respect to said body and formed with a plurality of seats in its upper side, and means for mounting said foot in said slot to selectively engage any of said seats.

6. The combination with a clamp having 80 a work supporting body, of a channel-shaped pressure foot having a pin connecting the flanges thereof substantially centrally of the length of said foot, and a support for said foot having a slot to receive said pin and a plurality of seats to selectively receive said pin to adjust said foot to accommodate work of various thicknesses.

7. The combination with a clamp having 85 a work supporting body and a pressure foot supporting rod pivotally mounted to swing toward and from said body, of a pressure foot, and a supporting member mounted on 90 said bar to permanently support said foot and formed with a plurality of seats to selectively receive said foot when the same is in operative position, said supporting member being also formed to permit said foot to automatically by action of gravity disengage itself from all of said seats when said supporting rod is swung away from 95 said body.

8. The combination with a clamp having 100 a work supporting body and a pressure foot supporting bar pivotally mounted to swing toward and from said body, of a pressure foot, a supporting member mounted on said 105 bar and formed with an inclined slot provided with a plurality of seats in its upper side, and means for permanently supporting said foot in said slot to selectively engage any of said seats for clamping and to automatically disengage said foot from all 110 of said seats when idle and move it toward one end of the slot.

RAYMOND W. BURNS.
